United States Patent Office

Des. 183,606

Patented Sept. 30, 1958

183,606

CHAIR

Henry P. Glass, Chicago, Ill., assignor to The Hale Company, East Arlington, Vt.

Application December 18, 1957, Serial No. 48,949

Term of patent 3½ years

(Cl. D15—1)

FIG. 1.

FIG. 2.

Fig. 1 is a perspective view of my ornamental design for a chair taken from the left front side thereof, and Fig. 2 is a rear perspective view of the chair in accordance with Fig. 1.

I claim:

The ornamental design for a chair, substantially as shown.
